ARNOLD MOETTELI, OF WINTERTHUR, SWITZERLAND, ASSIGNOR TO SULZER FRÈRES
SOCIÉTÉ ANONYME, OF WINTERTHUR, SWITZERLAND, A CORPORATION OF SWIT-
ZERLAND.

COOLING PLANT FOR COKE.

Application filed August 14, 1923. Serial No. 657,284.

To all whom it may concern:

Be it known that I, ARNOLD MOETTELI, a citizen of Switzerland, residing at Winterthur, Switzerland, Alte Romerstrasse 21, **5** have invented certain new and useful Improvements in Cooling Plants for Coke, of which the following is a specification.

The invention relates to a cooling plant for coke, in which the incandescent coke is **10** cooled by means of a current of gas circulated through a heat exchanging device. It consists in that the speed of flow of the gas current is regulated by means of a device, which automatically adjusts itself in accordance with the heat to be given up, and **15** also controls the fan. The device controlling the fan is thus controlled by the temperature of the coke.

On the drawing one mode of construction **20** of the device according to the invention is illustrated.

a is the cooling chamber, *b* the charging opening *c* the discharge outlet of a cooling receptacle adapted to receive the coke. The **25** charging opening can be closed by means of a movable hood *d* and the discharge outlet by a trap-door *e*. The cooling of the coke, as well as the utilization of the heat derived from it, is effected by the fan *f* forcing the gaseous contents of the cooling **30** receptacle in a closed circuit through the channel *g*, the pipe *h*, the boiler *i* and the coke.

As the rate of exchange of heat to the said **35** boiler depends on the speed of flow of the gas, but will fluctuate greatly with the temperature of the coke if the speed of flow of the said cooling gas remains constant, the plant is provided according to the invention **40** with a device adapted for varying the speed of flow of the gas, the said speed being controlled during the cooling operation in such a manner, that the variations in the rate of heat exchange caused by fluctuations in the **45** temperature of the coke are compensated automatically. The said device consists of an arrangement actuated by the lever *k* and serving for varying the supply of energy to the motor driving the fan. The arrangement **50** is such, that the supply of energy and the speed of the cooling gas increase when the said lever is raised, and decrease when the lever is lowered. The automatic adjustment of the lever *k* is effected by the expansion

and contraction of a bar-like piece *l* **55** fitted in the channel *g* and connected with the lever *k* through the lever *n* pivoted at *m* and the rod *o*. If the connecting lever and rods are dimensioned properly the lever *k* will be adjusted in accordance with the **60** mean temperature of the coke in such a manner that the rate at which heat is transferred will remain practically constant. In order to be able to adjust the transfer of heat to accord with the amount of heat required at the moment for the boiler, the pivot *m* of the lever *n* is connected with the piston *s* moving in the cylinder *r* by means of the link *p* and a further lever *q*, the lower side of the piston *s* being subjected to **65** boiler pressure and the upper side loaded with a spring. If the boiler pressure rises or falls in consequence of the reduced or increased consumption of steam, the piston *s* will rise and fall respectively and in this **70** manner will cause by adjustment of the levers *m* and *k* a reduction or increase in the rate at which heat is transferred to the boiler in accordance with the variations in steam consumption. In this manner it is possible to adjust automatically the heat to be transferred to the boiler so as to correspond with the heat required by the boiler. Obviously **75** the regulating device may be of any other suitable type. **80**

I claim:

1. In an apparatus for cooling incandescent coke by means of gases forced by a motor driven blower through the charge of coke in a container and through a boiler, the combination of the motor with a device for varying the speed of the motor, said device being automatically controlled by a thermostat under the influence of the mean temperature of the coke and by a regulating device under the influence of the steam produced in the boiler, whereby the blower is so driven that the speed of the cooling gases and the heat transmitted to the boiler corresponds at all times to the heat required by **100** the boiler. **90**

2. In an apparatus for cooling incandescent coke by means of gases forced through the charge of coke in a container and through a boiler, the combination of a motor driven blower forcing gases through the coke and boiler, a controller device for varying the speed of the motor, a thermostat **105**

actuated in accordance with the mean average temperature of the coke and communicating its motion to a rod, a steam pressure gauge connected to the boiler, a rod operated by said gauge and means for integrating the motion of the thermostat rod and gauge rod for transmitting the integrated motion of

the rod to the motor controller whereby the blower is driven at a speed variable with varying temperatures of coke and pressure of steam.

In testimony whereof I have affixed my signature.

ARNOLD MOETTELLI.
